Primary Examiner — Richelle G Shelton(74) *Attorney, Agent, or Firm* — Panitch Schwarze Belisario & Nadel LLP(57) **CLAIM**

The ornamental design for a fluid transfer assembly, as shown and described.

DESCRIPTION

FIG. 1 is a front perspective view of a fluid transfer assembly in accordance with my new design;

FIG. 2 is a front elevational view thereof;

FIG. 3 is right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The broken lines are directed to environment; the broken lines form no part of the claimed design.

1 Claim, 6 Drawing Sheets# US D801,522 S
